V. H. FAIRLESS,
ADJUSTABLE HEADREST FOR INVALIDS,
APPLICATION FILED AUG. 27, 1920.

Patented Jan. 25, 1921.

Inventor
Victor H. Fairless

By Wilkinson & Giusta,
Attorneys.

UNITED STATES PATENT OFFICE.

VICTOR HALE FAIRLESS, OF TRENTON, TENNESSEE.

ADJUSTABLE HEADREST FOR INVALIDS.

1,366,774.

Specification of Letters Patent. Patented Jan. 25, 1921.

Application filed August 27, 1920. Serial No. 406,333.

To all whom it may concern:

Be it known that I, VICTOR HALE FAIRLESS, a citizen of the United States, residing at Trenton, in the county of Gibson and 5 State of Tennessee, have invented certain new and useful Improvements in Adjustable Headrests for Invalids; and I do hereby declare the following to be a full, clear, and exact description of the invention, such as 10 will enable others skilled in the art to which it appertains to make and use the same.

My invention relates to an improved head and body rest for use in connection with a bed for the comfort and convenience of invalids, students, or others who by necessity 15 or choice spend a material portion of time in the reclining position.

It is customary generally to prop up the patient's or student's head or shoulders or 20 both with pillows, or sometimes the back of a chair, but such arrangements prove unsatisfactory in use.

My invention relates to an improved adjustable device adapted to support the head 25 and upper portion of the human body, which device may be conveniently attached to or removed from a bed by a single operation, and which may be used either alone or with pillows as may be preferred, and in which 30 the angle of the device may be quickly and conveniently varied when desired, so as to change the angle of tilt of the user.

My invention is intended to provide a light, inexpensive, and efficient device, which 35 holds firmly in place when in use, but which may be conveniently attached to the bed or removed when desired.

My invention will be more fully understood after reference to the accompanying 40 drawing which shows the frame of the head rest in full lines, and the bed in dotted lines.

A represents the main frame which is adapted to be attached to the bed and consists of a substantially U-shaped bar having 45 the legs A' flattened out and notched as at a', and the head of the frame is provided with two hook-shaped portions a² which are connected together by the cross bar A², the whole being formed of a single piece. All 50 the parts of the main frame are preferably rounded, as shown, including also the ends of the legs A'.

In order to protect the head boards of wooden beds from scarring, and to prevent 55 the head frames of metal beds from rattling, I provide soft cushioning means of any suit-

able form, such, for instance, as the rubber tubes B' and B² which may be slipped over the lower ends of the legs of the frame and moved to the desired place, being held in position by the elasticity of the rubber.

In combination with the main frame just described I use an adjustable supporting member comprising the rectangular metal frame D, preferably made of a solid rod, or 60 if desired a light tube may be used, the ends of which are welded together to form a continuous frame. The upper corners of this frame are bent to form U-shaped loops d to engage in the notches a' of the legs A.

The frame D is covered with any suitable flexible material, such as canvas, leather, or the like, but preferably canvas since this can be more conveniently washed when required.

In order to provide for the convenient 75 removal of the textile material I shape it in the form of a rectangular center E with four tapered tabs E', each tab being provided with eyelets e, the opposite tabs being connected together by lacings F and F', 80 which lacings should preferably be on the lower side of the frame D. By having two separate lacings the opposite tabs may be more conveniently secured together, but a single lacing may be used if desired.

The frame D may be made rectangular if desired, but I preferably have the sides bulging out slightly so that they will tend to prevent the sagging of the textile fabric when weight is applied thereto.

In operation, the hooks a² rest over the top of the head board or rail and the lower ends a of the legs drop down behind head of mattress. The eyes d of the frame D are engaged in the corresponding notches so as 95 to give the proper tilt to the frame D and the parts when in use are in the position shown in the drawing. The head rest may be used without pillows, or with one or more pillows as desired.

Whenever the canvas covering becomes soiled, or it is desired to change the same for any purpose, the lacing may be unrove and the canvas removed and another supplied, or the same canvas may be cleaned and 105 sterilized and returned to the initial position.

The two frames may also be conveniently sterilized when desired, and to facilitate this they are preferably galvanized or nickel-plated, or the parts of the same not subject 110 to wear may be covered with porcelain.

In order to prevent lodgment of germs or

dirt, and prevent injury to the bed clothes or the clothing of the wearer, all the parts should be rounded, including the edges of the main frame, also the notches formed in the main frame, as in devices of this kind it is especially desirable to prevent the accumulation of dirt in cracks or crevices.

It will be seen that the head rest may be supplied to or removed from the bed at a single operation, may be raised or lowered as desired, and that the cover E may be quickly removed and returned to the initial position when desired.

In order to fit bedsteads having backs of varying heights, I may provide main frames with legs of different lengths, probably main frames of two lengths would cover all normal conditions of the trade.

The invention is especially intended to provide a cheap and efficient implement which can be supplied in individual homes and used for the comfort and convenience of the occupants thereof.

It will be obvious that various changes might be made in the herein described construction, and in the combination and ar-

rangements of parts which could be used without departing from the spirit of my invention; and I do not mean to limit the invention to such details except as particularly pointed out in the claim.

Having thus described my invention what I claim and desire to secure by Letters Patent of the United States is:—

A head rest of the character described, comprising a main frame made of a single bar substantially in the form of an inverted U, having its legs flattened and provided with notches, and the upper ends of said legs curved to form supporting hooks adapted to slip over and rest on the head rail of the bed, with a cross bar connecting said hooks, and a second frame made substantially rectangular in shape, formed of a single rod having upwardly projecting loops formed therein at its upper corners, said loops being adapted to engage opposite notches in the main frame, and a cover made of flexible material detachably connected to said second frame, substantially as described.

VICTOR HALE FAIRLESS.
